UNITED STATES PATENT OFFICE

2,374,615

ELECTRIC SWITCH

Hershell A. Nickell, Schenectady, N. Y., assignor
to General Electric Company, a corporation of
New York

Application July 17, 1943, Serial No. 495,139

2 Claims. (Cl. 188—1)

My invention relates to electric switches, more particularly to shock responsive latches for electric switches, and has for its object a simple, reliable and inexpensive device of this character.

In carrying out my invention in one form I provide an unbalanced pivoted member provided with a plurality of latch teeth arranged to engage and secure a movable part of the switch or its operating mechanism. This pivoted member is normally held by a spring in a disengaged position and is provided with a weight or inertia member secured rigidly to the member and extending therefrom in a direction at right angles with the pivot of the member so as to be affected by shocks applied to the support for the switch, whereby the latch member is moved by a shock against the tension of its biasing spring into a position to engage and secure the movable part of the switch.

For a more complete understanding of my invention, reference should be had to the accompanying drawing, Fig. 1 of which is a front elevation view of an electromagnetically operated switch embodying my invention; Fig. 2 is a side elevation view of Fig. 1; while Fig. 3 is a fragmentary view showing a latching member in its latching or holding position.

Referring to the drawing, I have shown my invention in one form as applied to the latching of an armature 10 operated by a load responsive current coil 11 and normally biased about its pivot 12 by a helical compression spring 13 to its unattracted position shown in Figs. 1 and 2. The armature 10 is balanced about its pivot 12 by means of a counterweight 13'. It carries an adjustable operating screw 14 on its movable end, the lower end of which when the armature is moved to its attracted position engages and depresses a projection 15 on a latch member 16 made of a suitably electrically insulating material, such as a molded compound, and mounted on a pivot 17. This latch member 16 is biased clockwise about its pivot 17 by a helical compression spring 18 to the position shown in the drawing in which a projection 19 on its upper end lies over and thereby holds one end of an armature 20 and a bridging contact 21 carried thereby. The armature 20 is mounted at its other end on a pivot 22 and biased to an unattracted position in a clockwise direction, as seen in Fig. 2, by a helical compression spring 23. It is moved to its attracted position shown by energization of an operating coil 24.

The bridging contact 21 is triangular in shape and provided with a central aperture through

which extends a supporting stud 25, the lower end of which is secured to a block of electrically insulating material 20', the block being secured to the upper side of the armature 20. Mounted on the stud 25 is a helical compression spring 26, the lower end of which bears on the bridging contact member 21. In the latched attracted position of the armature 20 shown, the bridging member is held by the spring 26 with its two arms 27 and 28 in engagement with stationary connection and contact posts 29 and 30 thereby closing a circuit through itself between these two contact posts.

In accordance with my invention, I provide an unbalanced shock responsive inertia latch arm 31 for latching and securing the armature 10 in its unattracted position in the event of a shock applied to the supporting panel member 32 for the various parts. This latch arm is mounted on a stationary pivot 33 and is biased by a spring 34 in a clockwise direction about the pivot to the position shown in which the armature 10 is free to move to its attracted position. Carried by the armature 10 is a projection 35 provided with a knife edge 36 which is engaged by some one of a series of teeth 37 on the edge of the latch arm 31 adjacent the knife edge 36 so that, when the latch arm is moved counterclockwise about its pivot, some one of the teeth 37 engages the knife edge 36 and secures the armature 10.

For movement of the latch arm in response to shocks, I provide an inertia body 38 consisting of an arm having one end rigidly secured to the latch arm 31 at an intermediate point thereof by a riveted and welded joint 39. This member 38 extends substantially parallel with the armature 10 and the supporting panel 32 and laterally with respect to the latch arm 31 in a direction at right angles with the pivot 33. Its lower end, as seen in Fig. 2, is normally held by the spring 33 in engagement with an adjustable stop screw 40. Thus the inertia arm 38 statically unbalances the latch arm 31 about the pivot 33 of the latch arm.

In the operation of the device the bridging contact member 21 is moved to its closed circuit position shown by energization of the coil 24 which pulls the armature 20 to its attracted position where it is latched by the latching projection 19. The coil 24 is then deenergized. Its circuit may be controlled for example by means of a normally open push button switch, not shown. When the coil 11 is energized sufficiently to move its armature to its attracted position, the screw 14 engages the projection 15 and moves the latch

member 16 counterclockwise to release the armature 20 and thereby effect movement of the bridging member 21 to its open circuit position.

It will be understood that, in the event of a shock applied to the supporting panel 32, the counterbalanced armature 10 will tend to be moved toward its attracted position either directly by the shock or by a component of the shock whereby the latch member 16 would be moved to disengage the armature 20 and release the bridging contact for movement to its open circuit position. The shock, however, has the same effect but to a more pronounced extent in producing movement of the unbalanced inertia member 38, which extends substantially parallel with the armature 10, and thereby moves the latch arm 31 counterclockwise about its pivot to a latching position, as shown in Fig. 3, in which one of the teeth 37 has engaged the knife edge 36 and holds the armature 10 in its unattracted position against the effect of the shock. I contemplate that the armature 10 may be moved part way toward its attracted position before it is latched by the arm 31. Sufficient clearance, however, is provided between the end of the screw 14 and the projection 15 to provide for this movement of the armature 10. This clearance can be adjusted by suitable adjustment of the screw. Also, the spring 34 is much weaker than the spring 13 and, therefore, applies a much smaller biasing force to the latch arm 31 than is applied by the spring 13 to the armature 10. Consequently, the latch arm is very sensitive to shocks and moves in response to a shock more quickly than the armature so that some one of the teeth 37 engages and holds the armature before the armature has moved far enough to release the switch operating armature 20.

I contemplate that the load responsive current coil 11 will be connected in circuit with a device to be protected, such as an electric motor, so that in the event of a predetermined overload on the motor, the coil is energized sufficiently to attract the armature 10 and thereby effect movement of the bridging member 21 to its open circuit position whereby the circuit of the motor is opened. It will be understood that the bridging member 21 is connected by means of the connection posts 29 and 30 in the circuit of the motor in series with the coil 11. While the armature 10 is balanced by the weight 13' about its pivot support 12 and is furthermore biased to its unattracted position by means of the spring 13, the armature is nevertheless sensitive to shocks applied to the supporting panel 32. The armature is rendered more sensitive to shocks by reason of the fact that an appreciable amount of magnetic attractive force is applied to the armature by the load current in the coil

11 during normal operating load conditions in the circuit.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

10 What I claim as new and desire to secure by Letters Patent of the United States is:

1. The combination with a switching device provided with a support and a movable switch operating member mounted on said support of a knife-edge latching projection carried by said member, an arm extending substantially in the direction of movement of said switch operating member having one end mounted on a stationary pivot and provided with a plurality of teeth at 15 its other end in position to engage said knife-edge projection, a spring for normally biasing said arm to a disengaged position with respect to said knife-edge projection, an inertia member secured to said arm and projecting laterally from one side of said arm, and a stop engaging 20 said inertia member thereby to limit the position of said arm in response to the bias of said spring, said inertia member unbalancing said arm about its pivot to cause said arm to move in response to a shock applied to said support into an engaging latching position with said knife-edge projection.

2. The combination with a switching device provided with a support and a pivotally mounted 25 switch operating member mounted on said support, a knife-edge latching projection carried by said member, an arm mounted on a stationary pivot and extending substantially in the direction of movement of said knife-edge projection, a plurality of teeth on said arm in position to engage 30 said knife-edge projection, means normally biasing said arm to a disengaged position with respect to said knife-edge projection, an inertia member secured at one end to said arm 35 extending laterally with respect to said arm in a direction substantially parallel with said operating member, an adjustable stop engaging said inertia member thereby to limit the position of said arm in response to said biasing means, 40 said inertia member unbalancing said arm about its pivot to cause said arm to move in response to a shock applied to said support to bring one 45 of said teeth into latching engagement with said knife-edge projection before said operating member has moved far enough to carry out a 50 switching operation thereby to secure said operating member against movement in a switch operating direction.

HERSHELL A. NICKELL.
